Attorney

UNITED STATES PATENT OFFICE.

JOHN R. BRAZEALE, OF OZARK, MISSOURI.

GRIP WRENCH.

Application filed February 10, 1923. Serial No. 618,350.

To all whom it may concern:

Be it known that I, JOHN R. BRAZEALE, a citizen of the United States, residing at Ozark, in the county of Christian and State 5 of Missouri, have invented certain new and useful Improvements in a Grip Wrench, of which the following is a specification.

The present invention relates to a grip wrench and has for its principal object to 10 provide a structure whereby the range of the jaws may be easily and readily adjusted.

Another important object of the invention is to generally improve upon adjustable grip wrenches of this nature by providing 15 a simple and efficient structure which is reliable in operation, durable, light in construction, inexpensive to manufacture, attractive in appearance, and well adapted to the purpose for which it is designed.

With the above and numerous other objects in view as will appear as the description progresses, the invention resides in certain novel features of construction, and the 20 combination and arrangement of parts as 25 will be hereinafter more fully described and claimed.

In the drawing—

Figure 1 is an elevation of the wrench embodying my invention,

Figure 2 is a longitudinal section taken therethrough substantially on the line 2—2 of Figure 1, looking in the direction of the arrow,

Figure 3 is a perspective of the fixed jaw,

Figure 4 is an edge elevation of the upper portion of the wrench as shown in Figure 1,

Figure 5 is a transverse section taken substantially on the line 5—5 of Figure 1, looking in the direction of the arrow, and

Figure 6 is an edge view of the shank structure of the movable jaw.

Referring to the drawing in detail it will be seen that the preferred embodiment of the wrench consists of the main handle 1 upon which is disposed the fixed jaw A. The fixed jaw A is formed by having its body 2 integral with the shank 3 which in turn is integral with the handle 1 and a pair of thickening plates 4 are disposed one on each side of the body 2. A rib 5 is disposed on the shank 3 extending transversely of the handle 1.

A movable jaw B is associated with the 55 fixed jaw A and consists of three layers in the present embodiment which are secured

together so that it will be of equal thickness with the fixed jaw A. The outer layers terminate in extensions forming a shank 7. These extensions of the shank 7 are spaced 60 from each other and have teeth 8 arranged on one edge thereof adjacent the handle 1. One of the extensions of the shank 7 is provided with a groove 9 for receiving the rib 5, it being understood that when the jaws A 65 and B are assembled the shank 7 straddles the shank 3 and the jaws A and B may then be moved toward and away from each other.

An operating lever C is fulcrumed at 10 by a bolt or a rivet or in any other suitable 70 manner to the handle 1. This operating lever C consists of a handle portion 11 which is U-shaped in cross section for receiving the main handle 1. The fulcrum portion of the lever consists of two spaced extensions one on each side of the handle 1 and indicated by the numeral 12. The ends of these extensions 12 are provided with teeth 13 capable of meshing with teeth 8 on the shank 7. When the handle 11 of the lever C is disposed at an angle of approximately 95° with respect to the handle 1 the teeth 13 will be disengaged from the teeth 8 and the range of the jaws A and B may be approximately set. As the handle 11 is fulcrumed toward the handle 1 the teeth 13 will engage with the teeth 8 and further fulcruming of the handle 11 toward handle 1 will cause the moving of jaw B toward 80 jaw A for the purpose of gripping a nut or the like.

The edge of the handle 1 farthest from the handle 11 of the operating lever C is thickened by a rib 15 disposed on one side of the handle adjacent the edge and suitably fixed thereto. This rib not only strengthens the handle 1 but also prevents the hand from becoming cut or injured when squeezing the handles 1 and 11 towards each other. It is also to be noted that the U-shaped cross sectional structure of the handle 11 is formed with the space therein sufficiently small so that when the handle 1 is disposed within the handle 11 there will be a certain frictional engagement therebetween so that the wrench will normally remain in a closed position when situated in a tool box or in any other receptacle thereby preventing the parts thereof from accidentally disassembling.

Although I have described my invention with some degree of particularity, it is to

be understood that numerous changes in the details of construction and in the combination and arrangement of parts may be resorted to without departing from the spirit 5 of the invention as hereinafter claimed.

Having thus described my invention what I claim as new is:—

In a wrench of the class described, a fixed 10 jaw, a movable jaw, said fixed jaw consisting of three plates fixed together, the intermediate plate being extended to form a shank, and said shank being extended to form a handle, a rib disposed on the shank and extending transversely of the handle; 15 said movable jaw consisting of three plates, the two outer plates being extended to form shanks spaced from each other to receive

therebetween the shank of the fixed jaw, one of the shanks of the movable jaw being provided with a groove for receiving the 20 rib on the shank of the fixed jaw, the edges of the shanks of the movable jaw being provided with teeth; and an operating lever having a pair of spaced extensions pivoted to the handle and terminating in teeth for engagement with the teeth of the shanks of the movable jaw all in the manner and for the purpose specified. 25

In testimony whereof I affix my signature in presence of two witnesses.

JOHN R. BRAZEALE.
